UNITED STATES PATENT OFFICE.

WILBER E. ARNOLD, OF MADISONVILLE, OHIO, ASSIGNOR TO AMERICAN BANKERS SAFETY CO., OF NEW YORK, N. Y., A CORPORATION OF DELAWARE.

DESIGN FOR A VAULT-FRONT.

43,711.

Specification for Design.

Patented Mar. 18, 1913.

Application filed January 6, 1913. Serial No. 740,550. Term of patent 14 years.

To all whom it may concern:

Be it known that I, WILBER E. ARNOLD, a citizen of the United States, and residing at Madisonville, Hamilton county, State of Ohio, have invented a certain new, original, and ornamental Design for a Vault-Front, reference being had to the accompanying drawing, illustrating my design applied to a vault-front, which is shown in a face-view.

I claim—

The ornamental design for a vault front as shown.

WILBER E. ARNOLD.
